UNITED STATES PATENT OFFICE.

FELIX J. WATTS, OF BRONSON, MICHIGAN, ASSIGNOR TO HARRY A. DOUGLAS, OF BRONSON, MICHIGAN.

LOCK.

Application filed March 7, 1927. Serial No. 173,584.

My invention relates to locks which are adapted to transmit motion to devices that are to be controlled thereby such as switches pertaining to the ignition circuits of internal 5 combustion hydrocarbon engines employed in power plants of automotive vehicles.

The lock of my invention employs one or more detents serving to prevent the lock from transmitting movement in the absence 10 of a proper key and to permit or enable such movement in the presence of a proper key. These detents are related to a motion communicating bar which is operable by a key through the intermediation of a member 15 which is preferably separately formed from both the bar and the key, this bar being related to the object that is to be moved, such as the contact arm of an ignition switch. I desirably employ three detents in association 20 with this bar. Each of two of these detents is constrained to one position to prevent effective movement of the bar and is adjustable to another position by the proper key to free the bar of its restraining influence. 25 The remaining detent is desirably constrained to a position in which it normally permits effective movement of the bar and is adjustable to another position to prevent effective movement of the bar if it should 30 happen to be operated by an improper key or in an effort to pick the lock.

I will explain my invention more fully by reference to the accompanying drawing in which Fig. 1 is a longitudinal sectional view 35 of the preferred embodiment of my invention; Fig. 2 is a sectional view on line 2—2 of Fig. 1; Fig. 3 is a sectional view on line 3—3 of Fig. 1; and Fig. 4 is a circuit diagram illustrating one use of the invention.

I have shown my improved lock in controlling relation to the switch of an ignition circuit pertaining to an internal combustion engine. The circuit shown includes a primary winding 1 which has one terminal 45 grounded through a circuit breaker 2 whose contacts are shunted by a condenser 3. The other terminal of this winding is connected with a contact 4 carried upon one end of an arm 5 that is in the form of a bell crank and 50 which is operable by the lock of my invention, as will appear. The contact 6 which is complementary to the contact 4 is grounded through the battery 7. The secondary winding 8 has one terminal grounded through the 55 interrupter and has its other terminal con-

nected with the revolving arm 9 of a distributor whose waiting contacts 10 are successively engaged by said arm. These waiting contacts are connected with the electrodes 11 of spark plug or other gas igniting elements that are contained in the various cylinders of the internal combustion engine that is equipped with the ignition system.

The shaft 12 carries the switch arm 5 at the elbow of this arm. This shaft is journaled in a casing 13 of the locking mechanism of my invention and carries a motion communicating or transmitting bar 14 by which the shaft and the switch arm 5 are turned. This motion communicating bar is preferably in the form of a plate having slots or recesses 15, 16 and 17 formed therein. The casing 13 is hollow where said bar 14 is located to permit the bar to be swung in order that it may turn said bar. Detents 18, 19 and 20 are carried by an inner portion of the casing 13. These detents are in the form of pins each having a head or flange upon each end. The casing 13 is desirably initially made in separate pieces that are welded or otherwise assembled after the parts enclosed thereby have been disposed for location therein. The lower heads or flanges 18', 19' and 20' are pressed upon by coiled springs 21, these springs serving, when free to function, to project the reduced lower ends 18'', 19'', 20'' of the pins into the channel 22 that extends through the lock casing 13 parallel to the shaft 12 and bar 14 and which is adapted to receive a key 23. The key has a longitudinal slot 24 in one side thereof which is engageable with a rib 25 projecting into the channel 22 whereby the key is guided as it is inserted and removed from the lock casing. When the key is absent the flanges or heads 18'' and 20'' are placed out of register with the slots or recesses 15 and 17 so that the bar 14 may not then be moved, the proper key serving to elevate the pins 18 and 20 to bring their heads 18'' and 20'' into register with the recesses 15 and 17 in order that the bar may be moved. The head 19'' of the pin 19 is normally placed in register with the recess 16, the proper key 23 being formed so as not to disturb the position of this pin. If, however, an improper key is inserted which would move the pin 19 to bring its head 19'' out of register with the recess 16, such pin

would prevent movement of said bar. The key employed has a ward formation which will elevate the pins 18 and 20 to bring their heads 18^a and 20^a into register with the corresponding recesses, this ward formation, however, not disturbing the position of the pin 19. Said ward formation also includes a portion 23' which is engageable with the reduced end of a bar operating member 26 which is also preferably in the form of a pin having a flange or head 26' and a reduced key engageable end 26^a. A coiled spring 27 presses upon the head or flange 26' to press the reduced end 26^a in the path of the key. The upper end of the pin or member 26 has a cam formation 28 which is engageable with the end of the bell crank switch arm 5 that is remote from the contact 4. The arrangement illustrated is such that the bar 14 is adapted to be swung by the key in a direction to close the switch 4, 6 when the ignition circuit is to be employed. When the key is withdrawn, the spring 29 will open the switch, the switch being locked open until the proper key is again inserted. Features not herein claimed form the subject matter of a division of this application Serial No. 210,337, filed August 3, 1927.

Changes may be made without departing from the invention.

Having thus described my invention, I claim:

1. The combination with a motion communicating bar; of a key operated detent constrained to one position to prevent effective movement of the bar and adjustable to another position to free the bar of its restraining influence; a second key operated detent constrained to one position to permit effective movement of the bar and adjustable to another position to prevent effective movement of the bar; a member in moving relation with the bar when the bar is free of said detents; and a key receiving element with which said detents and member are assembled.

2. The combination with a motion communicating bar mounted to turn and having a recess therein; of a key operated detent having a portion receivable in said re-

cess and constrained to one position to bring said detent portion out of register with said recess to prevent effective movement of the bar and adjustable to another position to bring said detent portion into register with said recess to free the bar of its restraining influence; a member in moving relation with the bar when the bar is free of the detent; and a key receiving element with which said detent and member are assembled. 60

3. The combination with a motion communicating bar mounted to turn and having a recess therein; of a key operated detent having a portion receivable in said recess and constrained to one position to bring said detent portion into register with said recess to permit effective movement of the bar and adjustable to another position to bring said detent out of register with said recess to prevent effective movement of the bar; a member in moving relation with the bar when the bar is free of the detent; and a key receiving element with which said detent and member are assembled. 65

4. The combination with a motion communicating bar mounted to turn and having two recesses therein; of a key operated detent having a portion receivable in one of said recesses and constrained to one position to bring said detent portion out of register with said recess to prevent effective movement of the bar and adjustable to another position to bring said detent into register with the corresponding recess to free the bar of its restraining influence; a second key operated detent having a portion receivable in the other of said recesses and constrained to one position to bring this detent portion into register with said recess to permit effective movement of the bar and adjustable to another position to bring this detent portion out of register with said recess to prevent effective movement of the bar; a member in moving relation with the bar when the bar is free of said detents; and a key receiving element with which said detents and member are assembled. 70 75 80 85 90 95

In witness whereof, I hereunto subscribe my name.

FELIX J. WATTS.
